[57] **CLAIM**

The ornamental design for a frame for a tag, as shown and described.

DESCRIPTION

FIG. 1 is a front elevational view of the frame for a tag showing my new design, with the broken line showing for illustrative purposes only and forming no part of the claimed design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

*FIG. 1**FIG. 2**FIG. 3*

FIG. 4

FIG. 5

FIG. 6
